MULTINEEDLE SEWING MACHINE

Harold Kibitz, Adolph C. Suchy, and Joseph W. Droll, Chicago, Ill., assignors to J. W. Droll Company, Chicago, Ill., a corporation of Delaware

Application August 1, 1938, Serial No. 222,400

2 Claims. (Cl. 112—200)

The invention relates to multi-needle sewing machines of the looper-type which are adapted to form a double lock stitch, for stitching designs in the borders of mattresses, and are adapted to stitch varying designs in the border. For that purpose, it is necessary to vary the relative movements of the work and the stitching mechanism in different directions.

One object of the invention is to provide a stitching mechanism of the looper-type, which is adapted to sew different designs on the mattress-border produced by varying the relative movements in different directions of the work and the loopers and needles of the stitching mechanism.

Other objects of the invention will appear from the detail description.

In the drawings: Fig. 1 is a plan, parts being broken away, of a machine embodying the invention. Fig. 2 is a rear elevation, parts being shown in section. Fig. 3 is an end elevation of a portion of the machine. Fig. 4 is a section on line 4—4 of Fig. 2. Fig. 5 is a rear elevation, parts being shown in section, of the mechanism for operating the loop-retainers. Fig. 6 is a section taken on line 6—6 of Fig. 1. Fig. 7 is a section taken on line 7—7 of Fig. 2. Fig. 8 is a longitudinal section through the clutch-mechanism for shifting the work in opposite directions. Fig. 9 is a section on line 9—9 of Fig. 8. Fig. 10 is a section on line 10—10 of Fig. 8. Fig. 11 is a perspective illustrating a needle and looper after the needle has passed through the work and the looper is raised. Fig. 12 is a similar view illustrating the looper while it is entering the loop of the needle-thread on the right side of the needle. Fig. 13 is a similar view illustrating the needle withdrawn from the work and the retainer engaging the looper-thread and the loop of the needle-thread around the looper before the needle is passed through the work. Fig. 14 is a front elevation of the retaining device for the looper and needle-threads while it is forming the thread-triangle and deflecting the previously-formed loop of needle-thread. Figs. 15, 16, 17, 18 and 19 are diagrammatic views of the needle, looper and retainer illustrating their successive positions during the stitching. Fig. 20 is a detail perspective of the device for axially shifting the shaft which shifts the looper-carrying shaft.

The machine exemplifying the invention is carried by a supporting-frame 20. The stitching mechanism of the machine comprises: a horizontally reciprocating head 21 to which is fixed a series of needles 22, each of which is provided with an eye 22a and a longitudinal groove on its

right side for a needle-thread *a*; a series of arcuate loopers 26 adapted to coact with the needles, respectively, each being provided with a guide 26b and an eye 26a for a looper-thread *b*; a looper-supporting bar 27 which is fixedly mounted on a shaft 28 which is pivotally movable to swing the loopers vertically and is laterally reciprocable to shift the loopers from one side of the needles to the other to produce double locking stitches; and a series of retainers 30 which coact with the loopers and needles, respectively, and are mounted on a frame 29 which is movable in a circular path to correspondingly operate the retainers so that a triangle of the looper-thread will be maintained for the passage of the needle, and so that the locking loops of the looper-thread will be successively released when they are to be stripped from the needle and the looper.

The machine comprises relatively movable stitching mechanism and work-holding means to adapt the machine to stitch various designs in the work, such as a mattress-border 25, by relative vertical or lateral movements or by compounding such movements. In the machine illustrated the work is illustrated as movable relatively to the stitching mechanism but it will be understood that the invention may be embodied in a machine in which one of the relative movements may be effected by shifting the stitching mechanism relatively to the work. The means for carrying and moving the work comprises a carriage which is guided on the frame 20 to move laterally to effect the lateral movements of the work relatively to the stitching mechanism, and a pair of feed-rolls 23, 24 which are supported by, and movable laterally with, the carriage and are adapted to advance the work vertically through the machine. By selectively varying the lateral strokes of the work-carriage and the feed-strokes of the feed-rolls, or by compounding the lateral and feed-strokes, any desired variation of the designs of the stitching may be effected.

In the drawings only a single needle and looper are illustrated for clearness because the needles are alike in construction and operation and are similarly mounted on the head 21 and the loopers are alike in construction and are similarly mounted on the carrying-bar 27.

The stitching mechanism and work-feeding means are driven by gearing which is operated by power from electric motor 31 (Figs. 2 and 4) which is supported on frame 20. Said gearing comprises a belt 32 driven by the motor; a pulley 34 driven by belt 32; a shaft 33 journaled in a bracket 37, which is fixed to frame 20 and to

which pulley 34 is fixed; a beveled gear 36 fixed to the rear end of shaft 33; a countershaft 38 journaled in brackets 39, 39^a, 39^b, which are fixed on frame 20; and a beveled gear 40 fixed to shaft 38 and meshing with and driven by gear 36.

Needle-head 21 extends across the rear of the machine and is fixed to a pair of rods 41 which are slidably mounted in bearings 42. Said rods and head 21 are reciprocated so that the needles 22 will be passed through and withdrawn from the border 25 by means of crankpins 43 (Fig. 3) fixed to the outer end of shaft 38 and pitmen 44 which are operated by said crankpins and connected to reciprocate rods 41 and head 21. Each needle is supplied with a thread *a* from a source of supply, such as a spool. Each thread is subjected to tension, as well understood in the art, and directed by a guide *a*⁸ to the groove in the leftside of the needle 22 from which it passes through the eye 22^d of the needle.

Each looper-thread *b* is drawn from a suitable supply, such as a spool, and passes through a suitable tension-device 117 to a guide 118, from which it is directed to the guide 26^b in the looper and thence to the looper-eye 26^a in the outer end of the looper from which it passes to the work.

The mechanism for oscillating shaft 28 to swing bar 27 which carries the loopers 26, comprises a gear 102 (Fig. 1) fixed to rotate with countershaft 38; a gear 103 meshing with gear 102; a shaft 104 to which gear 103 is fixed and which is journaled in brackets 39, 39^a, 39^b; a crank 106 (Figs. 1 and 7) fixed to shaft 104; a link 107 operated by said crank; an arm 108 operated by said link and fixed to a shaft 109, which is journaled in bracket 39^b; an arm 110 fixed to shaft 109; a link 111, operated by arm 110; and an arm 112 fixed to shaft 28 which carries the loop-supporting bar 27. This mechanism rocks the loopers to cause them to pass the looper-thread around the needles and through loops of the needle-thread. Each looper 26 is fixed to a block 26^d, which is adjustably secured in bar 27, so the spacing between the needles and the loopers can be adjusted. Bar 27 is secured by clamps 27^a to looper-shaft 28 so the pivotal stroke of the loopers may be timed with respect to the needle-strokes.

Axial reciprocatory strokes are imparted to the looper-carrying shaft 28 and bar 27 to move the loopers 26 from one side of the needles to the other in forming double lock stitches with the loop-threads. The mechanism for reciprocating shaft 28 comprises an eccentric 113 (Figs. 1 and 3) fixed to one end of shaft 104; an arm 114 operated by said eccentric; and a bell-crank lever 115 which is pivoted on bracket 39 and provided with a horizontal arm adapted to be rocked vertically and a vertical arm connected by a link 116 to one end of shaft 28. A swivel connection is provided between shaft 109 and link 116 which permits said shaft to rotate independently of the link. This connection comprises a sleeve 200 fixed to shaft 109 and a member 201 which has one of its ends pivoted to link 116 and its other end connected to axially shift the sleeve and permit it to rotate relatively to member 201. Arm 114 is continuously operated to reciprocate shaft 28, and move the loopers horizontally from a vertical plane at one side of the needles to the other side to shift the loopers to a position in which the needle passes through a looper-thread triangle while the loopers are at the left side of the needle, and to cause the loopers to enter

the needle-thread loop on the right side of the needle to draw a loop of the needle-thread off the needle when the latter is retracted.

Each retainer 30 comprises a shank having an inclined terminal 30^a for engaging the looper and needle threads. The shank of each retainer 30 is fixedly secured in an arm 122 which is adjustably secured by a screw 123 to a frame 124 (Fig. 5) so the retainers may be properly timed and adjusted. Mechanism for shifting frame 124 and the retainers 30 comprises a bar 125 (Fig. 5) fixed to frame 124 and suspended from sleeves 126 which are simultaneously operated by eccentrics 127 on shafts 128 which are mounted in brackets 39. Each shaft 128 is driven by a toothed gear 129 fixed thereto and a gear 130 on the shaft 104. The eccentrics 127 are rotated simultaneously in the same direction to move the retainer-frame 124 and the retainers 30 in a circular path.

The padded mattress border 25 is guided vertically between a plate 49 (Figs. 1 and 4) which is fixed to brackets 39, 39^a, 39^b and a yielding pressure-plate 50 which is carried by the needle-head 21 and is secured to rods 51 which are slidably mounted and have a limited movement in said head. A compression spring 53 is applied to force plate 50 against the border during the strokes of the needles through the work and to release the border when the needles are withdrawn therefrom and during the vertical and lateral movements of the work relatively to the needles.

The laterally slidably carriage for the feed-rolls and the work comprises brackets 55 (Figs. 2 and 4) and shaft 56 and rod 57 which are slidably mounted in the supporting-frame 20. Horizontal guide-plates 46 (Fig. 4) and 47 for the work are carried by an angle-bar 76 which is fixed to brackets 55 to move the work laterally with the feed-rolls. Springs 48 are applied to plate 47 to press the work against the plate 46. The feed-rolls are adapted to advance the work vertically past the stitching mechanism and are mounted in the laterally movable carriage so that the work will be moved laterally with the carriage and can be advanced by the feed-rolls during the lateral movements of the carriage.

The mechanism for shifting the work-carriage laterally to produce a design of stitching in the border is driven from shaft 38 and comprises a cam 77. The contour of the periphery of the cam controls the intermittent lateral strokes of the carriage. By substituting cams of different shapes, the length of the lateral strokes may be varied relatively to the feed-strokes imparted to the work for variations in the design. Cam 77 is fixed to a shaft 78 (Figs. 2 and 4) which is journaled in brackets 79 supported from frame 20. Rollers 77^a engage the opposite sides of the periphery of cam 77 and are mounted in arms 77^b which are fixed to shaft 56 to reciprocate said shaft from said cam. The gearing for driving cam 77 comprises a cam 89 (Fig. 4) fixed to countershaft 38; an arm 86 fulcrumed at 87 and engaged by cam 89; a roller 88 carried by lever 86; a vertically slidable plunger 85, the upper end of which is engaged by roller 88; and an arm 84 for operating a one-way clutch to operate gearing for rotating cam 77 step-by-step. Arm 84 is fixed to a sleeve 83 which is rotatable on a shaft 82 (Fig. 8). The one-way clutch comprises a clutch-drum 95 provided with ratchet clutch-faces 96 and rollers 94 engaged by sleeve 83 and adapted to couple sleeve 83 and drum 95 for step-by-step rotation in one direction. A pinion 81 is

fixed to shaft 82 and drives a gear 80 which is fixed to shaft 78 to which cam 77 is replaceably secured. The retractile strokes are imparted to arm 84 by a spring 91 between said arm and the supporting-frame. A device for preventing overthrow during the retractile strokes of arm 84 comprises an arm 100 which is adapted to engage a part of bracket 79, a sleeve 99 to which arm 100 is fixed, and a one-way clutch which is reverse in its action from the clutch 94, 95 and comprises rollers 97 engageable by sleeve 99 and clutch-surfaces 98 on drum 95. When arm 100 strikes bracket 79, clutch 97, 98 will become effective to prevent further rotation of shaft 82 and the gearing driven thereby for rotating cam 77. A friction-band 101 is adapted to engage a brake-drum 102 which is fixed to clutch-drum 95. A spring 102 is applied to press brake-band 101 against drum 102 to retard the movements of the drum for causing the rollers engaged thereby to be quickly shifted into clutching positions.

Work feed-roll 23 (Fig. 4) is journaled in closed bearings at the upper ends of brackets 55 of the work carriage. Feed-roll 23 is operated step-by-step to advance the border 25 between the needle-strokes by a cam 58 fixed on counter-shaft 38; an arm 59 (Fig. 7) having a roller 60 engageable by said cam; a shaft 61 slidably mounted in the supporting-frame and to which arm 59 is fixed; an arm 62 fixed to shaft 61; a link 63; a pivoted-arm 64 which carries a spring-pressed pawl 65; a ratchet-wheel 66 pivotally supported on bracket 55; a pinion 67 fixed to rotate with ratchet-wheel 66 and a gear 68 fixed to roll 23 and engaging pinion 67. Roller 60 is movable across the face of cam 58 to permit the driving mechanism for roll 23 to move laterally with the roll when it is shifted to move the work laterally of the sewing mechanism. Feed-roll 24 is driven from roll 23 (Fig. 3) by a sprocket-wheel 69 fixed to roll 23, a sprocket-chain 70 driven by sprocket 69 and engaging an idler-roll 71 and a sprocket-wheel 72 fixed to roll 24 and engaged by a chain 73. The connection between link 63 and arm 64 is adjustable to vary the length of each stroke of arm 64 and correspondingly vary the feed-strokes of the feed-rolls. Thereby the vertical movements of the work can be varied relatively to its lateral movements, for changes in the design of the stitching.

Roll 24 is journaled in forked bearings in brackets 55 and is pressed against the work by levers 73 which are engaged by springs 74 and provided with screws 75 which engage the shaft of roll 24.

In the machine the stitching mechanisms may be arranged in rows one above the other, as illustrated in Fig. 5, so that the seams produced by one row of needles may intersect the seams of the other row. The entire series of needles, loopers and retainers are similarly operated to coact with one another, respectively, and, therefore, the description of a single stitching mechanism is applicable to all.

The operation of the machine will be as follows: the needle-thread *a* is threaded through needle-eye 22^a and secured in the work and the looper-thread *b* is secured in the work and threaded through guide 26^b and eye 26^a of the looper; the point of the needle will be passed through the work and to project from the front thereof while the looper 26 is lowered and at the right of the needle. Next, the needle will be slightly retracted to spread the right side of the

needle-thread away from the needle for the passage of the looper between the right side of the needle and the needle-thread. Next, the looper will be raised, operated laterally to the right and rocked downwardly to pass the looper-thread between the work and the looper-eye, between the right side of the needle and the needle-thread, as illustrated in Fig. 15. Next, the needle will be retracted through the work and a loop of the needle-thread will be formed around the looper and the looper-thread between the looper-eye and the work will extend through the loop of needle-thread in the looper, according to the design of stitching desired. While the needle is withdrawn the work will be shifted laterally and advanced vertically. When the work is shifted laterally to the left, the looper-thread, where it is attached to the work, will move toward the left with the work, thus tending to prevent the production of, or to narrow, the thread-triangle for the succeeding pass of the needle. Terminal 30^a of the retainer engages the looper-thread between the work and the looper-eye and also engages the loop of the needle-thread on the looper and presses them upwardly and to the right of the looper, thereby forming a thread-triangle for the needle at the right of the needle and holding the loop of the needle-thread clear of the needle, as illustrated in Fig. 16. The looper is then moved to the left while the retainer 30 is moving to the right and the thread-triangle is maintained. Next, the needle is pushed through the work while the looper is lowered and through the looper-thread triangle, as illustrated in Fig. 17. At this time the retainer, in its circular movement, has cleared the path for the needle. Next, the looper is raised to clear the needle, shifted laterally to the right of the needle, thereby passing the looper-thread around the needle. The needle is slightly retracted to loosen the needle-thread at the right of the needle between the needle-eye and the work and the looper is lowered, as illustrated in Fig. 18, to form a loop of the looper-thread around the needle and to pass the looper-thread between the looper-eye and the work through the loop of needle-thread on the right side of the needle. The needle is then retracted. Upon retraction of the needle, the loop of looper-thread which has been lapped around the needle, is drawn around the loop of the needle-thread and the looper-thread is drawn through the last formed loop of needle-thread. The tension on the threads during these movements tends to tighten the stitch. During each succeeding operation the same cycles will be performed to successively form double interlocking stitches between the needle-thread and the looper-thread, as illustrated in Fig. 19. The terminal 30^a of each retainer 30 is shifted in a circular path to engage and deflect the looper-thread to form a thread-triangle between the looper-eye 26^a and the work, for the needle, while the looper is at the left side of the needle, and is adapted to perform this function when the work is moved relatively to the needle in any direction in the plane of the work or transversely to the needle-strokes to adapt the machine for stitching different designs on the border. Each retainer also deflects the previously formed loop of needle-thread on the looper above the needle so it will be cleared by the needle during the succeeding stroke. In its travel in a circular path, each retainer crosses the needle path while the needle is retracted, remains effective while its terminal 30^a is above the needle, and moves to

the right and downwardly from the looper so the looper and needle-threads will slip off the looper during the retraction of the needle. During the succeeding stroke of the needle through the work, the retainer-arm 30 passes under the needle and to the left of the looper to become effective during the succeeding withdrawal of the needle from the work.

In stitching of designs which involve lateral relative movement of the stitching mechanism in the work, there is relative lateral movement between the stitches and the eye of the looper. When the movement of the work brings the completed stitch to the left, such movement tends to reduce or eliminate the thread-triangle, which is necessary on the right of the looper for the passage of the needle during its next succeeding stroke. In consequence, it is necessary that the retainers 30 be operated to hold the looper-thread to produce the thread-triangle. For this purpose, the retainers are operated in a circular path to move the upper portion of the thread-triangle to the right a sufficient distance to compensate for the movement of the work to the left and to form, at all times, a thread-triangle of sufficient width for the passage of the needle into it.

Between passes of the needles through the work the feed-rolls 23, 24 are operated to advance the work and the work-carriage is operated laterally according to the shape of cam 77. By means of cams of different shapes and variations of the length of the feed-strokes of rolls 23, 24, the design of the stitching produced by the stitching mechanism may be varied within a wide range.

The invention exemplifies a border stitching machine which is adapted for stitching various designs in the border which produces a double lock stitch by a looper-type of mechanism, as distinguished from the shuttle type. This looper-type renders reloading of the shuttles unnecessary and expedites the work. The retainers make it possible to shift the work in different directions relatively to the needle and looper between the stitches to insure the passage of the needle through the thread-triangle for the succeeding double lock stitches. This makes it possible to use the looper-type of stitching mechanism to produce different designs of stitching.

The invention is not to be understood as restricted to the details set forth, since these may

be modified within the scope of the appended claims, without departing from the spirit and scope of the invention.

Having thus described the invention, what we claim as new and desire to secure by Letters Patent is:

1. In a multiple needle sewing machine, the combination of a bed for the work, a plurality of stitching mechanisms each comprising a reciprocating needle and a thread-carrying looper mounted to swing into and out of a loop of needle-thread on the needle and for reciprocating movement from one side to the other of the needle, mechanism for relatively and conjointly moving the stitching mechanism and the work in different directions to produce an ornamental design of stitching, retainer devices associated with the loopers, respectively, and movable in a plane between the work and the looper and substantially parallel to the plane of the work, and mechanism for moving said devices so their operative ends will move in a completely circular path transversely of and across the needle path and to hold thread-triangles of looper-thread and engage the needle thread during the relative movements of the work and the stitching mechanisms in opposite directions.

2. In a multiple needle sewing machine, the combination of a bed for the work, a plurality of stitching mechanisms each comprising a reciprocating needle and a thread-carrying looper mounted to swing into and out of a loop of needle-thread on the needle and for reciprocating movement from one side to the other of the needle, mechanism for relatively and conjointly moving the stitching mechanism and the work in different directions to produce an ornamental design of stitching, retainer devices associated with the loopers, respectively, and movable in a plane between the work and the looper and substantially parallel to the plane of the work, a support for said devices and mechanism for moving the support for said devices so their operative ends will move in a completely circular path and transversely of and across the needle path and to hold thread-triangles of looper-thread so as to form a double lock stitch during the relative movements of the work and the stitching mechanisms in opposite directions.
